COMBINED HANDBAG AND UMBRELLA HOLDER

Leonard F. Soyka, 14 Devon Road,
Great Neck, N.Y. 11023

Filed Aug. 29, 1969, Ser. No. 18,922

Term of patent 7 years

Int. Cl. D3—02

U.S. Cl. D87—3

FIG. 1 is a front perspective view of a combined handbag and umbrella holder showing my new design;

FIG. 2 is a rear perspective view thereof; and

FIG. 3 is a side elevational view thereof.

The drawing has been lined for color.

I claim:

The ornamental design for a combined handbag and umbrella holder, substantially as shown and described.
